UNITED STATES PATENT OFFICE.

CHARLES C. RICHARDSON, OF WORCESTER, MASSACHUSETTS.

OIL-GUARD FOR SEWING-MACHINES.

SPECIFICATION forming part of Letters Patent No. 687,438, dated November 26, 1901.

Application filed August 1, 1901. Serial No. 70,502. (No model.)

To all whom it may concern:

Be it known that I, CHARLES C. RICHARDSON, a citizen of the United States, residing at Worcester, in the county of Worcester and 5 State of Massachusetts, have invented a new and useful Improvement in Oil-Guards for Sewing-Machines, of which the following, together with the accompanying drawings, is a specification sufficiently full, clear, and exact 10 to enable persons skilled in the art to which this invention appertains to make and use the same.

The objects of my present invention are to provide a neat and efficient protector or guard 15 device adapted for employment on sewing-machines for preventing the lubricating-oil that works out around the shaft-bearing between the balance-wheel and frame from being thrown off by the swift-running wheel and 20 spattering upon the tables, work, or clothing of the operators, also to provide a protecting-guard for the purpose specified having means for collecting the escaping oil and diverting the same to the interior of the arm or frame, 25 where it can be deposited in the usual drip-pan or in other suitable receptacle beneath the sewing-machine. These objects I attain by the mechanism illustrated in the drawings, wherein—

30 Figure 1 represents an elevation view of the inner side of the balance-wheel having the flaring barrier-rim attached thereto. Fig. 2 is a longitudinal central section of mechanism embodying my invention. Fig. 3 is an 35 end view, and Fig. 4 a side view, showing the collector or guard ring and its support separate from other parts. Fig. 5 is a back view, and Fig. 6 a side view, of the bell-shaped barrier-rim separate from other parts; and 40 Fig. 7 illustrates a modification in the form of barrier-rim.

My invention consists in an oil-guard mechanism for sewing-machines comprising a flaring or bell-shaped barrier-rim tightly fixed in 45 or upon the nave or hub at the inner end face of the balance-wheel and projecting therefrom to cover the joint and surround the end of the shaft-bearing where the operating-shaft is journaled in the arm or frame of the machine, 50 and, combined with said flaring barrier-rim, a hollow-shaped annular guard or internally-chambered collector-ring that surrounds the

said rim and bearing and is disposed in a manner to receive the oil that is thrown or drips from the peripheral edge of said barrier-rim. 55 The collector or guard ring is provided with a spout or tube at its lower part, leading therefrom through an opening in the sewing-machine arm and from which the oil can drip within the interior of the frame into the pan 60 usually arranged beneath the machine.

Referring to the drawings, the part marked A represents a portion of the arm or upper frame of a sewing-machine of ordinary well-known construction—as, for instance, a 65 “Singer” manufacturer’s machine.

B indicates the balance and band wheel, having the hub mounted on the operating-shaft C, which latter turns in the bearing a, formed as a projecting part of the frame A, 70 all in well-known manner. The end of the hub runs adjacent to the end of the bearing.

D indicates a circular barrier or bell-shaped rim having its smaller end securely attached to the inner end of the band-wheel hub with 75 a close or non-leakable joint. Said rim projects over the end of the bearing a without contact therewith, its lip e standing out some distance from the bearing. Said rim is preferably struck up by aid of dies from sheet 80 metal and formed with a shoulder 3 and neck 4, that is driven tightly onto or into a receiving-shoulder formed in or upon the hub of the wheel concentric with the axis.

F indicates the internally-chambered oil- 85 collecting annulus or guard-ring, formed of sufficient internal diameter and breadth to surround and inclose the edge of the rim D and adapted to stand adjacent thereto, but without contact therewith at any part. Said 90 ring F is supported in position between the frame A and wheel B in suitable manner for retaining it in concentric relation to the shaft and rim and normally stationary by connecting with the frame. In the present instance 95 and preferably the support consists of a spring plate or arm G, connected to the ring and having its lower part secured to the frame at a convenient position below the line of the wheel B by a screw or bolt h, as indicated in 100 Fig. 2. The guard-ring F is best formed of sheet metal, die-drawn into the required shape, with inwardly-turned lips on the edges, as shown. The diameter of opening through the

front lip 5 of the ring F is greater than the diameter of the rim D; but the opening through the other lip 6 may be of less diameter than the end of the barrier-rim D, the better to 5 prevent spattering toward the frame. At the lower part of the ring I arrange an inclined tube or spout I, leading to the interior of the frame A (see Fig. 2) through a hole therein. The collected oil can pass from the interior 10 of the ring F and drip into the pan (not shown) beneath the sewing-machine or to any suitable receptacle into which the tube may be led. In the preferred arrangement of the parts the oil-hole m in the bearing a is covered by the 15 ring F when at its normal position; but by reason of the spring action of the support G the ring can be pressed forward sufficiently to facilitate oiling in said hole m, and the ring returns to normal position when the pressure 20 is relieved.

In some instances the rim D may be made, as shown in Fig. 7, with a curled-in lip e^2 and provided with holes n for the delivery of the oil to the guard-ring in lieu of a straight lip, 25 as e.

In the operation any oil escaping from the bearing end is caused to flow on the inner surface of the flared rim and to pass from the edge e thereof, whether the wheel is running or idle, into the annular chamber of the 30 guard-ring F, and thence flows to the interior of the frame or arm A, so that no oil is spattered about the exterior or thrown from the machine to injure work and clothing.

35 These oil-guards can be applied to sewing-machines now in use without altering the machines and at comparatively little cost and labor.

What I claim as of my invention, and desire 40 to secure by Letters Patent, is—

1. An oil-guard mechanism for the purpose set forth, comprising a circular barrier-rim having a cylindrical attaching-neck, for its

45 tight connection to the band-wheel, and revoluble with the band-wheel and shaft, a stationary, internally-chambered annulus or guard-ring presenting an inwardly-open groove or channel, with inclosing lips, surrounding the outer edge of said barrier-rim adjacent to but not in contact therewith, a 50 drip-tube leading from the channel of said guard-ring, and an arm attached to and adapted for supporting said guard-ring in connection with a sewing-machine frame.

2. The combination with the frame-arm 55 having the projecting shaft-bearing, the operating-shaft, and the balance or band wheel in a sewing-machine; of the bell-shaped or flaring barrier-rim rigidly fixed to said wheel, and projecting from the hub, over the bearing 60 concentric with the axis, an internally-channelled guard-ring surrounding the delivery edge of said barrier-rim, a tubular exit from the channel of said guard-ring leading into the interior of the arm, and a bracket 65 or ear-plate supporting said guard-ring in connection with the frame.

3. The combination, with the machine-frame having the projecting bearing with the oiling-hole therein, the operating-shaft rotatable in said bearing, and the wheel mounted on said shaft adjacent to the bearing; of a barrier or deflecting rim carried on the end of the wheel and extending over said bearing, an internally-chambered oil-collecting annulus surrounding said rim and bearing, and a yieldable resilient supporter attaching said annulus to the frame, and permitting resilient displacement thereof to afford access to the 70 oiling-hole.

75 Witness my hand this 31st day of July, 1901.

CHARLES C. RICHARDSON.
